UNITED STATES PATENT OFFICE.

PETER JAEB, OF ELK RIVER, MINNESOTA.

BARN-DOOR LOCK.

Application filed May 9, 1924. Serial No. 712,137.

To all whom it may concern:

Be it known that I, PETER JAEB, a citizen of the United States, residing at Elk River, in the county of Sherburne and State of Minnesota, have invented certain new and useful Improvements in Barn-Door Locks; and I do hereby declare the following to be a full, clear, and exact description of the invention, such as will enable others skilled in the art to which it appertains to make and use the same.

This invention relates to a lock or latch adapted to hold two relatively movable members in stationary and aligned position and particularly to such a lock or latch adapted for use with swinging doors, such as a heavy garage or barn door. As is well known, the barn and garage doors are often made of considerable size and great shocks and stresses are encountered by the locks and latches holding the same.

It is an object of this invention to provide a simple and rugged latch or lock for a door which can be operated from either side of said door.

It is a further object of the invention to provide such a simple and rugged latch comprising pivoted grip handles at either side of said door, one of said handles having a latch connected to its pivot adapted to engage a keeper and said handles having means connecting the same and passing through the doors to cause them to swing in unison.

It is more specifically an object of the invention to provide a simple and rugged latch or lock comprising oppositely disposed and swinging bail handles at each side of the door having laterally extending pivot rods at their upper ends which are journaled in brackets secured at each side of said door, respectively, the said pivot rods having arms thereon extending substantially in opposite directions, which arms are connected by a link passing through the door. One of said pivot rods being extended and offset to form a latch, together with a keeper with which said latch is adapted to co-operate. The swinging bail handles with the pivot rods and arms constitute a pair of bell crank levers connected together for movement in unison.

These and other objects and advantages of the invention will be fully set forth from the following description made in connection with the accompanying drawings in which like reference characters refer to the same parts throughout the different views, and in which,

Fig. 1 is a view in side elevation of a portion of one side of the door and door jamb showing the lock and keeper therefor;

Fig. 2 is a vertical section on the line 2—2 of Fig. 1, as indicated by the arrows, some of the parts being shown in different position in dotted lines; and

Fig. 3 is a horizontal section taken on the line 3—3 of Fig. 1, as indicated by the arrows.

Referring to the drawings, the device comprises oppositely disposed grip handles 1 and 2, said handles being at opposite sides of the swinging door 3 and disposed adjacent the free edge thereof. While any convenient and suitable form of handle may be used, in the embodiment of the invention illustrated, said handles are shown as of substantial bail shape having their top and bottom sides diverging slightly. The handles are thus substantially in the shape of a trapezoid having an open side. The handles 1 and 2 are further shown as being formed of a round rod and each handle has projecting at each side thereof at its top portion, horizontal portions 1^a and 2^a, respectively. The portions 1^a and 2^a on the respective handles are journaled in brackets 4, one of said brackets being secured at each side of the door 3, which bracket 4 comprises spaced ears 4^a and a U-shaped flat flange 4^b connecting the same, said flange being apertured to receive the attaching headed and nutted bolts 5. It will be noted that the bracket 4 in which are journaled the portions 2^a has its flange portion 4^b disposed upwardly, while the bracket 4 in which are disposed the portions 1^a has its flange portion 4^b disposed downwardly, the ears 4^a on the respective brackets being offset vertically of the door.

The handle 1 has an arm 1^b projecting outwardly and upwardly, as shown in Fig. 2, which arm is secured to the central part of its portion 1^a. The handle 2 has a similar arm 2^b projecting downwardly, as seen in

Fig. 2, from the central part of its portion 2^a, said arms 1^b and 2^b thus being vertically aligned with their respective handles. Obviously the handles 1 and 2, carrying the pivot members 1^a and 2^a, respectively, and the arms 1^b and 2^b, respectively, constitute a pair of bell crank levers having their oppositely extending working arms connected together for movement in unison by means of the link 6. Thus, when either handle of the bell crank levers is manipulated, the eccentric latch 2^a will be moved. The arms 1^b and 2^b are pivotally connected by a flat link 6 extending through a slot in the door 3 so that the handles 1 and 2 are caused to swing in unison. The link 6 is shown as projecting a short distance beyond the arm 1^b. This extended link is provided so that the hole for connecting the arm 1^b can be placed at different points to accommodate doors of different thicknesses. One end of the portion 2^a of the handle 2 is extended and provided with an offset portion 2^c forming an eccentric latch and this latch is adapted to co-operate with a keeper 7 formed of a flat bar bent to form a hook having a recess in its upper side with a downwardly curved or inclined outer side 7^a. The keeper 7 is secured to the door jamb 8 by suitable headed and nutted bolts 9.

In operation, the door will be closed or opened from either side by engagement of handles 1 or 2. The handle taken hold of will be swung outwardly, as shown in dotted lines in Fig. 2 and this swinging motion will, through the arms 1^c and 2^c, and the link 6, swing the opposite handle outwardly in unison. As the handle 2 swings outwardly, the latch 2^a is swung upwardly out of alignment with the keeper 7 so that it will pass over the top of said keeper and the door may be swung open. When the door is closed and it is desired to latch the same, either handle is raised and after the portion 2^c passes inside of the sides 7^a of the keeper the handle is swung downwardly or toward the door and the latch 2^a wedges down against the sides 7^a of the keeper.

From the above description it is seen that applicant has provided an extremely simple latch or lock for a door or other member. The latch can be ruggedly made to form a very efficient and suitable piece of heavy hardware for barn doors, garage doors or other similar heavy doors. The parts of the device are easily made and the same is very easily and quickly installed. The operation of the device is simple and positive and the device has no tendency to become disarranged. The device has been fully and amply demonstrated in actual practice and found to be very successful and efficient for the purposes intended.

It will, of course, be understood that va-

rious changes may be made in the form, 65 details, arrangement and proportions of the parts without departing from the scope of applicant's invention, which, generally stated, consists in a device such as shown and described and defined in the appended 70 claims.

What is claimed is:

1. A door lock comprising a pair of oppositely disposed handles, one mounted on either side of a door, said handles each carrying a bell crank lever pivoted on an axis substantially parallel to the sides of said door, the working arms of said levers extending in opposite directions, a link traversing the thickness of said door and pivotally connecting said working arms, a latch swingable with one of said handles at one side of said door and a keeper adapted to be engaged by said latch. 75

2. A door lock comprising a pair of oppositely disposed swingable handles, one mounted on either side of a door, said handles each carrying a bell crank lever pivoted on an axis substantially parallel to the sides of said door, the working arm of one of said levers extending upwardly and the working arm of said second lever extending downwardly, a link traversing the thickness of said door and pivotally connecting said working arms, an eccentric latch member rigidly connected to one of said handles and swingable therewith, and a keeper adapted to be engaged by said latch. 90

3. A door lock comprising a pair of oppositely disposed swingable lever handles, one mounted at either side of a door, each having a transverse pivot revoluble on an axis substantially parallel to the sides of said door, one of said pivots having an extended outwardly curved portion forming an eccentric latch swingable with said handles, and a keeper with which said latch is adapted to engage. 100

4. A door latch comprising a bail handle disposed at each side of the door, a rod extending at each side of said handle adjacent its top portion, a bracket having spaced ears secured at each side of said door in which ears said rods are journaled, said handles being oppositely disposed and locked between said ears, an arm projecting downwardly from one of said rods, an arm projecting upwardly and outwardly from the other of said rods between said ears, a link pivotally connecting said arms extending through said door, one of said rods having its end extended and offset to form an eccentric latch, and a keeper having a downwardly curved side with which said latch is adapted to engage. 110

5. A door lock comprising a handle disposed at each side of the door, a rod extending at each side of said handle, a bracket

secured at each side of said door carrying means for journaling said rods, said handles being oppositely disposed, an arm projecting downwardly from one of said rods, and

5 an arm projecting upwardly from the other of said rods, a link extending through said door and pivotally connecting said arms, one

of said rods carrying an eccentric latch at one end thereof and a keeper with which said latch is adapted to engage. 10

In testimony whereof I affix my signature.

PETER JAEB.
